DUST SEAL FOR ADJOINING RAILROAD CARS

Clarence P. Nelson, Chicago, Ill.

Application June 21, 1945, Serial No. 600,711

8 Claims. (Cl. 105—20)

1

The present invention relates generally to dust seals. More particularly the invention relates to that type of dust seal which is applied to the outer abutting diaphragm plates of a pair of adjoining vestibule variety railroad cars and serves as a medium or instrumentality for preventing dust and other matter on the outside of the cars from passing between the outer diaphragm plates and entering the car vestibules.

It has heretofore been proposed to utilize as a dust seal of this type, a one-piece strip of rubber or other dust and fluid impervious material and to secure the strip in place by clamping the side margins thereof to the inner margins of the outer diaphragm plates by way of metallic strips and bolts extending through aligned holes in the strips, the side margins of the dust strip and the inner margins of the diaphragm plates. In practice it has been found that a dust seal in the form of a one-piece strip is objectionable for several reasons, even though it fulfills its intended purpose. In the first place, such a seal requires considerable time to detach in connection with uncoupling of the two cars because it is necessary to release one of the side margins of the dust strip by withdrawing the bolts and metallic clamping strip which are associated therewith. Secondly, such a dust seal has but a short life because repeated strip releasing operations which are necessary during servicing and inspection of the cars result in tearing of, and other damage to, the dust strip. Thirdly, complications arise when a different car is substituted for one of the two cars and it is found that the substituted car and the other car both have dust strips on their outer diaphragm plates or it is found that neither of the two cars has a dust strip attached to its outer diaphragm plate.

The primary or principal object of the present invention is to provide a dust seal of the type under consideration, which is an improvement upon, and eliminates the deficiencies of, previously designed dust seals and is characterized by the fact that it consists of a pair of complementary, normally side by side, strip-sections, the inner margins of which are permanently attached to the inner margins of the outer diaphragm plates of the two cars and the outer margins of which are provided with quickly detachable connecting means. By providing a dust seal of the last mentioned character the two sections of the dust seal may be readily detached or disconnected when it is necessary to uncouple the two cars and it is possible in connection with substitution of a different car for one of the two cars readily to con-

2

nect the two strip-sections, provided that the substituted car, like the car for which it is substituted, has a complementary strip-section.

Another object of the invention is to provide a dust seal of the last mentioned type and character in which the quickly detachable connecting means between the outer margins of the strip-sections is in the form of a slide fastener arrangement, and the outer margins of the strip-sections have outer and inner flaps which when the seal is in its operative position as the result of the two complementary strip-sections being connected together by the quickly detachable connecting means, are arranged in abutting relation and serve to protect such means against dust, rain and snow.

A further object of the invention is to provide a dust seal of the aforementioned character in which the two complementary strip-sections are formed with longitudinally extending pleats in order that they are free to stretch laterally when the two cars to which the seal is applied travel around a curve.

A still further object of the invention is to provide a dust seal of the type under consideration which is generally of new and improved construction, may be manufactured at a low and reasonable cost, efficiently and effectively fulfills its intended purpose and possesses comparatively long life.

Other objects of the invention and the various advantages and characteristics of the present dust seal will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a fragmentary perspective showing a dust seal embodying the invention in operative relation with the outer abutting diaphragm plates of a pair of adjoining vestibule variety railroad cars;

Figure 2 is a fragmentary perspective of one of the cars after it has been uncoupled from the other car and its strip-section has been detached or disconnected from the complementary strip-section on the outer diaphragm plate of the other railroad car;

Figure 3 is an enlarged horizontal section of the dust seal illustrating in detail the manner in

which the inner margins of the complementary strip-sections are permanently attached to the inner margins of the abutting diaphragm plates and the outer margins of the strip-sections are detachably connected together when the strip is in its operative position;

Figure 4 is a vertical section on the line 4—4 of Figure 3;

Figure 5 is an enlarged horizontal section on the line 5—5 of Figure 4;

Figure 6 is a fragmentary detail of the slide fastener arrangement constituting the quickly detachable connecting means between the outer margins of the two complementary strip-sections; and

Figure 7 is a section taken on the line 7—7 of Figure 6 and showing in detail the construction and arrangement of the outer and inner flaps which are applied to the outer margins of the strip-sections and serve to cover the slide fastener arrangement and protect it against dust, rain and snow.

The dust seal which is shown in the drawings constitutes the preferred form or embodiment of the invention and is illustrated in connection with a pair of adjoining vestibule variety railroad cars C and C¹. As hereinafter described more in detail the seal serves as a medium or instrumentality for preventing dust and other matter on the outside of the cars from infiltrating the joint between the cars and entering the car vestibules. The two cars are of standard or conventional design and construction and comprise bodies c having at the ends thereof wheel carrying trucks (not shown). The ends of the cars that are in abutting or adjoining relation embody fixed or rigid frame structures c¹ and buffer plates c² and these, together with outer diaphragm plates c³ and accordion type diaphragms c⁴, define communicating vestibules c⁵ whereby passengers and railroad personnel may walk from one car to the other. The outer diaphragm plates c³ abut against one another when the cars C and C¹ are coupled together and consists of horizontally extending bottom members c⁶, horizontally extending top members c⁷ and vertically extending side members c⁸. They are supported by upper rod and spring assemblies c⁹ and lower rod and spring assemblies c¹⁰ so that they are inwardly yieldable in the direction of the car bodies c. The upper assemblies c⁹ extend between the upper portions of the frame structures c¹ and the top members c⁷ of the outer diaphragm plates c³ and the lower assemblies extend between the lower portions of the frame structures and the bottom members c⁶ of the diaphragm plates, as shown in Figure 4. The vertically extending side members c⁸ of the diaphragm plates are disposed in laterally spaced relation and have their upper ends connected to the ends of the top members c⁷ and the lower ends thereof connected to the ends of the bottom members c⁶, as shown in Figure 2. The inner margins of the top members c⁷ and the side members c⁸ of the outer diaphragm plates c³ are provided with integral flanges c¹¹ and these extend inwards at right angles to the plates and are of inverted U-shaped contour. The diaphragms c⁴, like the flanges c¹¹, are of inverted U-shaped contour. They are V-shaped in cross section, as shown in Figures 3 and 4, and are disposed directly inwards of the diaphragm plates c³. The inner margins of the diaphragms are suitably connected to the frame structures c¹ and the outer margins of the diaphragms are

connected or attached to the top and side members of the outer diaphragm plates.

As its parts or components the dust seal comprises a pair of complementary strip-sections 10 and these are associated with the outer diaphragm plates c³, respectively, and are positioned in opposed or side by side relation when the two cars C and C¹ are coupled together. Preferably the strip-sections 10 are formed of heavy canvas or other flexible material which is chemically treated so that it is impervious to dust and fluid. As shown in the drawings, the two strip-sections are of inverted U-shaped contour and extend around and lie within the inwardly extending flanges c¹¹ on the top and side members of the outer diaphragm plates c³. The ends of the strip-sections 10 are shown in the drawings as terminating adjacent the lower ends of the side members c⁸ of the diaphragm plates. If desired, however, the ends of the strip-sections may be extended so that they may be arranged in lapped relation on the buffer plates c² of the two railroad cars. The strip-sections are folded longitudinally to form full length pleats 11. The latter permit the strip-sections to stretch or expand laterally when the two cars C and C¹ travel around a curve. The corners of the pleats are preferably provided with longitudinal stitching 12 in order that the pleats tend to remain in their folded or pleated condition. The inner margins of the strip-sections 10 are provided with double folds and have longitudinal stitching 13 in order to form three thickness hems 14. The latter fit flatly against the inner faces of the flanges c¹¹ on the top and side members of the outer diaphragm plates c³ and are clamped permanently in place by way of metallic clamping strips 15 and bolts 16. The clamping strips 15 are disposed within, and shaped conformably to, the flanges c¹¹. The shanks of the bolts 16 extend through aligned holes in the clamping strips 15, the hems 14 and the flanges c¹¹, as shown in Figure 5. The hems 14 are interposed between the flanges and the clamping strips and are securely clamped in place when the nuts on the shanks of the bolts are fully tightened. It is contemplated that the inner margins of the strip-sections 10 will remain in permanently connected relation with the flanges c¹¹. The strip-sections 10 are of such width that the dust seal as a whole is capable of expanding to the necessary extent to take care of sharp turns without placing the canvas of which the strip-sections are formed under tension.

The outer margins of the strip-sections 10 are longitudinally doubled back and stitched to form hems 17 and are provided with quickly detachable connecting means whereby they may be connected together when the two cars C and C¹ are coupled together. The quickly detachable connecting means is in the form of a slide type or variety fastener arrangement (zipper) and comprises a longitudinal series of equidistantly spaced fastening members 18 on one of the hems 17, a longitudinal series of laterally spaced coating fastening members 19 on the other hem 17, and a pair of slide members 20. The fastening members of each series are of conventional design or construction and have bifurcated inner ends in straddled relation with the hem that is associated therewith. The outer ends of the fastening members have laterally extending lugs on one side thereof and lug receiving sockets or cavities on their other side. The slide members 20 are normally in associated relation with the two series

of fastening members and are adapted when slid in one direction to bring the outer ends of the fastening members of one series into interfitting or interlocked relation with the outer ends of the fastening members of the other series, and when slid in the opposite direction to separate the two series of fastening members. One of the slide members is adapted to slide back and forth between the central portion and one end of the two series of fastening members and the other slide member is adapted to slide back and forth between the central portion and the other end of the two series of fastening members. The slide fastener arrangement is such that when the two slide members are slid outwards and then downwards for the purpose of separating the two series of fastening members the end portions of the strip-sections 10 may be detached from one another. When the slide members are disposed at the central portions of the two series of fastening members the slide fastener arrangement is closed with the result that the outer margins of the two strip-sections 10 are in connected relation throughout the length thereof and the dust seal as a whole seals the two outer diaphragm plates c^3 so that dust and other matter on the outside of the two cars are prevented from passing into the vestibules c^2 . In order to protect the slide fastener arrangement constituting the quickly detachable connecting means between the outer margins of the strip-sections 10 against dust, rain and snow the outer margins of the strip-sections are provided with outer flaps 21 and inner flaps 22. The outer flaps 21 are in the form of longitudinally folded or doubled over strips of chemically treated canvas and are connected to the outer margins of the strip-sections by stitching 23. They extend lengthwise of the outer margins of the strip-sections 10 and are arranged so that their outer margins abut against each other when the slide fastener arrangement is in closed position wherein it serves to connect the two strip sections. The inner flaps 22, like the outer flaps 21, are in the form of longitudinally folded or doubled over strips of chemically treated canvas and extend lengthwise of the outer margins of the strip-sections 10. They are held in place by the stitching 23 and are arranged so that the outer margins thereof abut against one another when the two strip-sections are connected together as shown in Figure 7. When the two strip-sections 10 are connected together by the slide fastener arrangement the outer and inner flaps 21 and 22 cover the coacting fastening members 18 and 19 of the slide fastener arrangement and thus protect them against dust, rain and snow accumulating thereon.

When the two cars C and C^1 are coupled together and the two longitudinally pleated strip-sections 10 have the outer margins thereof in connected relation the dust seal as a whole seals the two outer diaphragm plates c^3 against inflow into the vestibules of dust and other matter, as heretofore pointed out. When it is desired to uncouple the two cars for service, inspection, or other purposes, the outer margins of the two strip-sections 10 are disconnected by sliding the slide members 20 outwards and then downwards to the ends of the two series of fastening members on the hems 17. After so sliding the slide members the ends of the outer margins of the two strip-sections are separated. At the conclusion of this operation the two strip sections are completely disconnected and it is possible to uncouple and then separate the two cars.

The herein described dust seal effectively and efficiently fulfills its intended purpose and is characterized by the fact that the two strip-sections thereof may be quickly and readily disconnected when it is desired to uncouple the two cars with which the dust seal is associated. It is also characterized by the fact that it possesses long life and is capable of being manufactured or produced at a low cost. The slide fastener arrangement for connecting the two complementary strip-sections 10 is of the interchangeable variety and hence when one car is disconnected or uncoupled from the other car another car may be coupled to the other car and a dust seal effected, provided that the said another car is provided with a strip-section which is a complement of the strip-section 10 on the said other car.

The invention is not to be understood as restricted to the details set forth since these may be modified within the scope of the appended claims without departing from the spirit and scope of the invention.

Having thus described the invention what I claim as new and desire to secure by Letters Patent is:

1. A seal adapted to prevent infiltration of dust and other matter between the abutting frame-like outer diaphragm plates of a pair of coupled-together vestibule variety railroad cars and comprising a pair of complementary separately formed opposed strip-sections formed of flexible, dust and fluid impervious material, extending around the inner marginal portions of the top and side parts of the diaphragm plates, having certain of the side margins thereof connected to said marginal portions, respectively, and provided on the other side margins thereof with quickly and readily releasable means for connecting them together.
2. A seal adapted to prevent infiltration of dust and other matter between the abutting frame-like outer diaphragm plates of a pair of coupled-together vestibule variety railroad cars and comprising a pair of complementary separately formed strip-sections of inverted U-shaped contour, formed of flexible, dust and fluid impervious material, positioned in opposed relation, having certain of the side margins thereof connected, respectively, to the top and side parts of the diaphragm plates, and provided on the other side margins thereof with quickly and readily releasable means for connecting them together.
3. A seal adapted to prevent infiltration of dust and other matter between the abutting frame-like outer diaphragm plates of a pair of coupled-together vestibule variety railroad cars and comprising a pair of complementary separately formed strip-sections of inverted U-shaped contour, formed of flexible, dust and fluid impervious material, positioned in opposed relation, having certain of the side margins thereof connected, respectively, to the inner marginal portions of the top and side parts of the diaphragm plates, and provided on the other side margins thereof with quickly and readily releasable means for connecting them together in a dust-tight manner.
4. A seal adapted to prevent infiltration of dust and other matter between the abutting frame-like outer diaphragm plates of a pair of coupled-together vestibule variety railroad cars and comprising a pair of complementary separately formed longitudinally pleated strip-sections of inverted U-shaped contour, formed of flexible dust and fluid impervious material, positioned in opposed

relation, having certain of the side margins thereof connected to the top and side parts of the diaphragm plates, and provided on the other side margins thereof with quickly and readily releasable means for connecting them together.

5. A seal adapted to prevent infiltration of dust and other matter between the abutting frame-like outer diaphragm plates of a pair of coupled-together vestibule variety railroad cars and comprising a pair of complemental separately formed opposed longitudinally pleated strip-sections of inverted U-shaped contour, formed of flexible, dust and fluid impervious material, having certain of the side margins thereof connected, respectively, to the inner marginal portions of the top and side parts of the diaphragm plates, and provided on the other side margins thereof with quickly and readily releasable means for connecting them together in a dust-tight manner.

6. A seal adapted to prevent infiltration of dust and other matter between the abutting frame-like outer diaphragm plates of a pair of coupled-together vestibule variety railroad cars and comprising a pair of complemental separately formed opposed strip-sections formed of flexible, dust and fluid impervious material, extending around the inner marginal portions of the top and side parts of the diaphragm plates, having certain of the side margins thereof connected to said marginal portions, respectively, and provided on the other side margins thereof with quickly and readily releasable means for connecting them together, and also with longitudinally extending substantially full length side flaps positioned in abutment with one another and in lapped relation with the connecting means.

7. A seal adapted to prevent infiltration of dust and other matter between the abutting frame-like outer diaphragm plates of a pair of coupled-together vestibule variety railroad cars and comprising a pair of complemental separately formed strip-sections of inverted U-shaped contour, formed of flexible, dust and fluid impervious material, positioned in opposed relation, having certain of the side margins thereof connected, respectively, to the top and side parts of the diaphragm plates, and provided on the other side margins thereof with quickly and readily releasable means for connecting them together, and also with inner and outer longitudinally extending substantially full length flaps positioned normally in abutment with one another and overlapped relation with the connecting means.

8. A seal adapted to prevent infiltration of dust and other matter between the abutting frame-like outer diaphragm plates of a pair of coupled-together vestibule variety railroad cars and comprising a pair of complemental separately formed opposed longitudinally pleated strip-sections of inverted U-shaped contour, formed of flexible, dust and fluid impervious material, having certain of the side margins thereof connected, respectively, to the inner marginal portions of the top and side parts of the diaphragm plates, and provided on the other side margins thereof with quickly and readily releasable means for connecting them together in a dust-tight manner, and also with longitudinally extending substantially full length side flaps positioned normally in abutment with one another and in lapped relation with the connecting means.

CLARENCE P. NELSON.
